UNITED STATES PATENT OFFICE.

CHARLES W. BOWEN, OF LYNN, MASSACHUSETTS, ASSIGNOR TO UNITED SHOE MANUFACTURING CORPORATION, OF PATERSON, NEW JERSEY, A CORPORATION OF NEW JERSEY.

METHOD OF MAKING HEELS.

1,288,492.

Specification of Letters Patent. Patented Dec. 24, 1918.

Original application filed December 9, 1912, Serial No. 735,750. Divided and this application filed July 18, 1918. Serial No. 245,481.

To all whom it may concern:

Be it known that I, CHARLES W. BOWEN, a citizen of the United States, residing at Lynn, in the county of Essex and State of Massachusetts, have invented certain new and useful Improvements in Methods of Making Heels; and I do hereby declare the following to be a full, clear, and exact description of the invention, such as will enable others skilled in the art to which it appertains to make and use the same.

This invention relates to a method of making heels and more particularly to a method by which heels may be made in multiple continuously.

Heretofore three general methods have been devised and used for making heels from whole lifts. By the first method, most generally in use, the heels are built singly by hand in a form which aligns the component lifts, using the same form repeatedly after each ejection of a completed heel. An example of the type of machine employed in practising this method is shown in the patent to Eliphalet A. Tripp No. 1,056,720, granted March 18, 1913, on an application filed June 9, 1909. By the second method, little practised at present, a mechanical collecting device for the component lifts is substituted for the hand operation of the first method and this device delivers the collected lifts to an aligning device, the entire operation being repeated for each heel that is built. An example of the type of machine for practising this method is shown in the present applicant's prior Patent No. 1,146,996, granted July 20, 1915, on an application filed August 16, 1907. It will be recognized by those skilled in the art that the two methods just described are defective in that the requirement for completing one heel before another can be commenced reduces the output of the operative and renders the entire operation slow and undesirable. Accordingly by the third method it has been proposed to employ an apparatus which will enable the operative to build a plurality of heels at the same time, the mode of operation being such that completed heels are being delivered continuously while other heels are still in process. By using this method the delay heretofore present in starting successive heel building operations is eliminated permitting the operative to obtain a materially increased

yield. An example of the type of machine 55 employed in practising this method is shown in the application of Erastus E. Winkley, filed originally August 26, 1910, Serial No. 579,109, renewed July 6, 1917, Serial No. 179,096.

While the Winkley application discloses broadly the idea of building heels in multiple, in practising that method with the apparatus which is illustrated in his patent, and which he deemed most suitable, the delivery of completed heels is limited to one heel for each third handling or deposit of a series of lifts at the building station. It will be obvious to those skilled in the art that the most rapid method of building heels in 70 multiple would be that in which a completed heel is delivered at each successive handling or deposit of a series of lifts at the building station. By perfecting the multiple method in the manner just described the delivery of 75 heels in the same period of time is increased three-fold over the delivery from the Winkley apparatus.

The object of the present invention is to improve upon present known methods of 80 making heels in multiple by introducing into the building process certain steps which provide for the delivery of a completed heel at each successive handling or deposit of a series of lifts at the building station.

The practice of the method is facilitated by the use of some simple apparatus which will assist the operative in handling and depositing a series of lifts at a time, and will permit each such series to be advanced simultaneously beyond the stations of deposit and intermittently through succeeding stations. As illustrative of one form of apparatus that may be employed a diagrammatic representation is given of the essential features of 90 a heel building machine illustrated and described in the inventor's co-pending application filed December 9, 1912, Serial No. 735,750, from which this present application is a division.

The improved method will be explained with the assistance of the accompanying drawings in which:

Figure 1 is an elevational view of the lift collecting apparatus, employed in one form of the machine of said parent application, at the building station to which the successive series of lifts are delivered,

Fig. 2 is a plan view of the apparatus shown in Fig. 1, and

Fig. 3 is a diagram illustrative of the successive lift collecting steps required when using apparatus of the type illustrated in Figs. 1 and 2.

In practising the novel method the heel-lifts are obtained from a series of sources of supply which are arranged in a row to facilitate handling the lifts in series. Where heels of the "Cuban," "military" or like type, having a slanted or pitched back, are to be produced, a lift of a different size will be obtained from each source of supply. To 10 simplyfy an explanation of the method it will be assumed that a five-lift heel, having a pitched back, is to be produced, the largest lift being obtained from the source of supply at the right-hand end of the series and the smallest lift from the left-hand end.

Since heels are to be built in multiple lifts must be obtained from the sources of supply and transferred to the building station in successive series, and in the present 25 method the lifts deposited at the building station at each lift handling operation are equal in number to the number of lifts in the heel to be built. Any convenient device for handling lifts in series may be used. 30 for example pickers of the type illustrated in Figs. 68 and 69 of the patent to Emmet Horton No. 760,791, granted May 24, 1904, or, if the lifts are to be obtained from strips of sheet material, dies such as illustrated in 35 said parent application, may be used.

When employing the form of apparatus disclosed more particularly in Fig. 10 of said parent application each series of lifts is deposited at a building station having the 40 form of a flat bed 2 provided with a slot 4 extending from end to end thereof. The lifts of each series are deposited at different stations on the bed, over its slot, and the corresponding lifts of each successive series 45 are deposited at the same station. In order that the successive deposits of lifts may superpose the lifts on each other so as to build heels in multiple suitable mechanism may be employed for intermittently advancing all the lifts simultaneously, from the 50 stations of deposit to the next adjacent stations in the row, during the intervals between the successive deposits of lifts.

One form of feed mechanism, which acts 55 directly on the heel-piles formed by the deposited lifts, is illustrated in said parent application. In using this mechanism a series of feed fingers 6, equal in number to the number of lifts in the heel, are intermittently projected upwardly through the slot 4 in the rear of (at the breast end) each of the deposited lifts, then are moved in the line of the row a sufficient distance to advance the lifts to the next adjacent stations 60 in the row, and then are withdrawn and

returned to their original positions. To impart this four-motion feed movement to the fingers 6, they are secured to a carriage 8 which is adapted to reciprocate back and forth a distance equal to the space between adjacent stations. The carriage 8 is reciprocated by a cam 10 and lever 12 carrying a gear segment 14 which meshes with a rack on a sub-carriage 16. Rolls 18 on the carriage 8 co-act with cam-surfaces 20 on the 75 sub-carriage which terminate in shoulders 22. The sub-carriage is supported on a slide 24, sustained on a sub-bed 26, by rolls 28 contained between pairs of stops 30 and 32 on the slide. A friction device 34 engaging the slide and sub-bed restrains the movement of the slide. Upright guides 36 on the slide are engaged by projections on the carriage 8 and prevent horizontal movement of the latter relative to the slide. The 85 mode of operation will be obvious from the foregoing description. A movement of the gear segment to the left in Fig. 1 will first by moving the sub-carriage 16 relatively to the carriage 8, raise the fingers 6, then the two carriages move together thus advancing the lifts which are in front of the fingers. On the return swing of the gear segment the fingers are first dropped below the bed 2 and then returned to their first position. 90 Side guides 38 may be provided for alining the superposed lifts properly.

In this way the lifts are advanced step-by-step through each of the stations beyond the station of deposit and after each 100 step the pile is increased by one lift, so that finally after passing the last station in the row the heel piles are complete. A graphic representation of the manner in which the heel piles collect additional lifts 105 at each successive lift handling operation is given in Fig. 3 of the drawings.

It is preferred to secure together the lifts comprising each heel. An adhesive is the most suitable medium for this purpose and in the apparatus disclosed in said parent application a bar 40 is provided above the assembling bed 2, which sustains a series of paste brushes 42. These brushes depend into positions between the stations at which lifts are deposited so that as each series of deposited lifts is advanced they are swept beneath the brushes and receive a coating 115 of paste on their upper exposed faces. The brushes may be replenished with paste from 120 time to time by the means described in said parent application.

When the heel piles are completed they are delivered successively at one end of the 125 row of stations at each forward step, and thereafter the lifts of each delivered heel may be additionally secured by driving a nail through them. It may be here stated that some shoe manufacturers secure the lifts by nails alone but obviously it is within the 130

scope of the present method to employ only one or both securing steps as may be desired. The nailing mechanism may be like that disclosed in said prior Patent No. 1,446,996 5 hereinbefore referred to, the nail magazine being shown at 44, the raceway at 46 and the driver rod at 48. The delivered heels are fed in a row, successively, to the nailing mechanism and each, after having 10 received a nail therethrough, is ejected by the other advancing heels.

Referring again to the diagram of Fig. 3 it will be observed that if the sequence of steps there set forth is followed, starting 15 with a single deposit of lifts at line *a*, incomplete heels will be delivered at the 2nd, 3rd and 4th handling of the lifts, namely at the left on lines *b*, *c*, and *d*. This waste may be avoided by completing the partially built 20 heels by a hand operation. In practice, however, this is taken care of by the operative who, before beginning to deposit the lifts in series, will place one, two, three and four lifts on the 2nd, 3rd, 4th and 5th stations 25 respectively as shown on line *d* and thus provide for the delivery of a complete heel at each subsequent deposit of a series of lifts. By taking this precaution, the stations are always loaded with lifts as on 30 lines *e* and *f* after each lift handling operation.

Obviously a heel of any desired size may be built in multiple simply by varying the 35 number of lifts composing each deposit. In this connection particular attention is called to the fact that in this application the term "lift" is used in an inclusive sense as defining any blank capable of being utilized in building heels, irrespective of the particular shape which the blanks may have 40 when they are first collected in the form of a heel pile.

Those skilled in the art will recognize that the apparatus illustrated is not the only apparatus which may be employed to assist in building heels in multiple when utilizing the principles enunciated in the foregoing description, and reference should be made to the appended claims which define the true 50 scope of the invention.

Having thus described the novel process

and the mode of building heels when employing its underlying principle, what is claimed as new, is:

1. The method of building heels in multiple which includes the steps of depositing in a row a series of lifts, equal in number to the number of lifts in the heel to be built, each lift at a different station; intermittently advancing said lifts simultaneously 60 through succeeding stations in the row; depositing an additional series of lifts, equal in number to the first series, at each period of rest; and applying paste to each series; whereby as the lifts are advanced additional lifts are simultaneously collected and a heel is delivered at one end of the row of stations at each forward step. 65

2. The method of building heels in multiple which includes the steps of depositing in a row a series of lifts, equal in number to the number of lifts in the heel to be built, each lift at a different station; intermittently advancing said lifts simultaneously through 70 succeeding stations in the row; depositing an additional series of lifts, equal in number to the first series, at each period of rest; whereby as the lifts are advanced additional lifts are simultaneously collected and a heel is delivered at one end of the row of stations 75 at each forward step; and securing together 80 the lifts of each delivered heel.

3. The method of building heels in multiple which includes the steps of repeatedly 85 depositing successive series of lifts at a series of stations in a row, the corresponding lifts of each series being deposited each at the same station, and the number of lifts in each series being equal to the number of lifts in the heel to be built; intermittently advancing all the 90 deposited lifts simultaneously, from the stations of deposit to the next adjacent stations in the row, during the intervals between the successive deposits of lifts; whereby the heel piles increase in height at each advance 95 and a heel of the desired height is delivered when the number of stations through which the lifts have been advanced is equal to the number of lifts required in the heel; and securing together the lifts comprising each 100 heel.

CHARLES W. BOWEN.
